United States Patent Office

Des. 177,407
Patented Apr. 10, 1956

177,407

STONE FOR COSTUME JEWELRY OR SIMILAR ARTICLE

Adolph Katz, Providence, R. I., assignor to Coro, Inc.,
New York, N. Y., a corporation of New York

Application October 25, 1955, Serial No. 38,558

Term of patent 7 years

(Cl. D45—1)

Fig. 1

Fig. 2

Fig. 1 is a plan view of a stone for costume jewelry or similar article, showing my new design.

Fig. 2 is an edge view thereof.

I claim:

The ornamental design for a stone for costume jewelry or similar article, substantially as shown.
